UNITED STATES PATENT OFFICE

153,683

DESIGN FOR A PAPER NAPKIN HOLDER

Paul B. Hamilton, Birmingham, Ala.

Application February 21, 1947, Serial No. 137,072

Term of patent 3½ years

(Cl. D44—24)

To all whom it may concern:

Be it known that I, Paul B. Hamilton, a citizen of the United States, residing at Birmingham, in the county of Jefferson and State of Alabama, have invented a new, original, and ornamental Design for a Paper Napkin Holder, of which the following is a specification, reference being had to the accompanying drawings, forming a part thereof.

I claim:

The ornamental design for a paper napkin holder, as shown.

PAUL B. HAMILTON.
